UNITED STATES PATENT OFFICE.

JEREMIAH A. SCRIVEN, OF NEW YORK, N. Y.

UNION-SUIT.

1,228,977.

Specification of Letters Patent.

Patented June 5, 1917.

Application filed April 9, 1913. Serial No. 759,919.

To all whom it may concern:

Be it known that I, JEREMIAH A. SCRIVEN, a citizen of the United States, and resident of the borough of Manhattan, city, 5 county, and State of New York, have invented certain new and useful Improvements in Union-Suits, of which the following is a specification.

My invention relates to union garments 10 and has for its object the production of suits of this character which shall meet more satisfactorily than union suits heretofore known the convenience and comfort of the wearer and which by reason of 15 their special construction shall be more durable and from the manufacturing standpoint, more correctly made.

Reference is had to the accompanying drawings in which several types of union 20 suits embodying my invention are illustrated and in which Figure 1 is a front view of a garment constructed according to my invention; Fig. 2 is a view of the crotch portion thereof with the rear flaps pulled 25 forward; Fig. 3 is a rear view of a portion of another type of garment embodying my invention; Fig. 4 is a rear view of still another form of garment showing my improvement; Fig. 5 is a view similar to Fig. 30 3 and illustrating still another type of garment in which my improvement is included; and Fig. 6 is a view similar to Fig. 2 showing another form of my invention.

For convenience the first garment illustrated will serve as an example to show the 35 nature of this invention. The garment comprises the usual upper or body portion A, and for the purposes of this invention this body portion may be constructed in 40 any desired manner, with or without elastic insertions at various appropriate points, sleeveless or with sleeves, and any suitable material may be used. The material employed in Fig. 1 is cambric or nainsook, 45 the garment being particularly designed for summer use. The elastic waist band B is shown as attached to the lower edge of the body portion A by means of the ridge or seam C. The body portion A, as well as 50 the elastic insertion B, is open at the front. The lower part of the garment is shown as attached by the ridge or seam C' to the lower part of the elastic insertion B, and the material composing the lower part of 55 the garment is in the case of Fig. 1, formed of the same material as that which is used

for the upper or body portion A. The rear of the elastic insertion B is shown as relatively high up upon the back, the object of this construction being described later. The 60 lower part of the garment D in Fig. 1 is formed, speaking generally, of two halves, one for each leg. The upper part of one of these halves having a terminal edge D' extending from the crotch to the elastic insertion, said edge lying in the same general line as the terminal edge of the insertion and of the body portion. For convenience we may call this line the button line, because it carries the buttons X down the 65 front of the garment. The upper edge of this part of the lower portion of the garment is attached to the waist portion of the garment all the way from the button line to a point beyond the middle of the center 70 of the back and the corresponding portion of the other part of the lower portion of the garment is similarly attached beginning at the button hole line and running also to a point beyond the center of the back, so 75 that it overlaps at the rear the button section. The two leg portions at the rear are provided with free disconnected terminal edges E and E' and the two sections again 80 become joined together along a line located 85 slightly to the rear of the crotch where, as in the upper construction, the button hole section overlaps the button section to approximately the same extent as these two 90 parts overlap at the waist. At the point where these two parts overlap at the crotch, 95 there is a straight seam extending clear across the garment from one leg opening to the other. This straight seam F, shown in Fig. 2, serves for the main portion of its 100 length to connect the tubular parts of the leg portion and at the crotch this seam serves to unite the front portion of the garment with the rear portion, in overlapping condition as described. The front of the 105 garment is provided with turned over or hemmed portions G and H and G' and H'. The two hems H and H' meet in the crotch region where the lowermost inner edges of 110 these hems are fastened together by stitches whose general direction is longitudinally of the garment. This connection is shown in the drawing as comprising a small gusset I, the edges of which are attached to the inner edges of the hems H—H' by stitching indicated in dotted lines in Figs. 1, 2, 3 and 6. These rows of stitches run longitudi-

nally of the garment and of the edges of the hems H—H' and serve to unite permanently the lowermost inner edges of the fabric forming the front opening of the 5 garment.

Constructed according to these principles, it will be seen that the front of the garment is wholly independent, from the standpoint of the designer, of the rear part of 10 the garment. This enables the manufacturer to give special attention to the shape, configuration, design and construction as well as fit of the front part of the garment from the waist down. The same thing is 15 true of the rear of the garment. By joining the front and the rear together by the transverse seam at right angles to the length of the garment, the suit becomes a harmonious and uniform entity, each part 20 of which has, however, been constructed with an eye to its own specific requirements.

The rear overlapping portions of the two leg sections are shown as being hemmed at J and J', the opening being of relatively 25 great length. The length of this opening is determined by the point of attachment of the overlapping part to the waist of the garment and for that reason, where it is desired to have a very long opening, the waist band 30 or insertion is caused to pass high up across the back of the garment. Many modifications of my idea are possible, as for instance, that the terminal portions J and J' of the rear opening may be made elastic, so long as 35 the main principle of the invention is retained, which so far as concerns this rear opening, consists in the overlapping portion joined in the crotch by a transverse seam to the front portion of the garment which is 40 built up quite independently of the rear portion. The extent to which the rear portions overlap must, of course, be largely left to the designer and that is an added advantage flowing from the construction of this 45 application because the designer of the rear portion is free to work out his ideas practically without reference to the manner in which the front of the garment is designed. The elastic fabric, if employed for these 50 rear overlapping parts, may, of course, be as wide or as narrow as desired for special cases and may extend down into the leg portions to any extent that may be requisite, even as far as the leg openings themselves. 55 In this latter case, as shown in Fig. 3, the cross seam F would unite a front part made of cambric with a rear part made of knitted or other elastic fabric throughout the total extent of the seam F.

60 It is also apparent, as shown in Fig. 4, that the elastic waist portion can be entirely dispensed with and the rear overlapping flaps of the body portion be carried as high up as the line of the arm pits. In that case 65 it is advisable to employ the button and

button hole K. The direction of elasticity in the various elastic parts of the garment is indicated in the drawings by the fine lines intended to represent the ridges of the knit material. Thus the waist band is shown 70 throughout as elastic in a direction longitudinally of the garment while the rear flaps are elastic transversely of the garment.

I have found that in some cases, the overlapping rear portions may be advantageously duplicated. In that case the rear part of the garment assumes the form of a flap L which may be provided with insertions L² of elastic material extending into the leg portion if desired. These insertions L² as 80 illustrated may be connected by means of an elastic strip L³, the wales of which run at an angle to those of the insertion L², as shown in Fig. 5, the said flap L being secured in position on the wearer with two or more 85 buttons L' at the top or with a string. The crotch construction in that case is, however, the same as before, except that in this particular drawing, the seam F is not necessarily a continuous seam made with the same 90 thread, but may be made of seam sections all located in the line F, thereby permitting the front and rear portions of the garment to be constructed as independent units and united by the transverse seam F, that idea being of 95 the essence of this invention. In this form the gusset I' may also be of elastic fabric. Instead of the single seam F, two of such 100 seams may be used, inclosing between them an additional strip of material running transversely through the garment and through the crotch portion thereof, and that strip of material may be elastic, or otherwise, as desired. An illustration of this variation is shown in Fig. 6.

Obviously the waist band need not be entirely elastic, but may consist of an elastic portion in the back of such shape as will afford a slight elastic resistance in a longitudinal direction to the overlapping rear flaps. 110 The elastic portions, may, however, be entirely dispensed with.

It will be seen from the foregoing that my union suit differs from all union suits heretofore known in consisting, so far as the 115 lower portion of the garment is concerned, of two individual parts which are individual with respect to the construction of the front portion and the rear portion thereof in contradistinction to the older union suits 120 which have separately made or separated right and left leg portions. In other words in my garment the front portions are independently united; the rear portions are fashioned independently of the front portion and 125 thus when front and rear configurations have been determined and the front parts of the garment united together, the garment is finished by means of the transverse seam F which unites the independently united front 130

portions of the garment with the overlapping rear portions. According to my construction, the right and left leg portions can also be given distinctive construction just as well as the front and rear portions of each leg. It will be observed that in spite of the fact that I am able by this invention to give any desired shape or configuration to any part of the front or rear portion of the legs, the fabric which composes the front and rear portion of each leg is continuous (or substantially continuous when insertions are used) and that the seam F not only unites the edges of the continuous fabric but preserves the special configuration and construction which has been given to the front part of the garment and to the rear part of the garment.

Having thus described my invention what I claim is:

1. A union suit having a front opening from the neck to the crotch, the edges of said opening normally overlapping each other to an equal extent from the neck to a point below the waist, the lower terminal portion of said edges being positively spaced apart immediately above the crotch whereby the edges of said opening are pre-

vented from overlapping at said point, a rear portion open from the crotch to the 30 waist and a transverse seam to unite said rear portion with said front portion in the crotch.

2. A union suit having a front opening from the neck to the crotch, the edges of 35 said opening normally overlapping each other to an equal extent from the neck to a point below the waist, the lower terminal portion of said edges being positively spaced apart immediately above the crotch 40 being united by seams extending longitudinally of the garment and of said edges whereby the edges of said opening are prevented from overlapping at said point, a rear portion open from the crotch to the 45 waist and a transverse seam to unite said rear portion with said front portion in the crotch.

In testimony whereof, I have hereunto set my hand in the presence of two subscribing 50 witnesses.

JEREMIAH A. SCRIVEN.
